The ornamental design for an ear piercer, as shown and described.

DESCRIPTION

FIG. 1 is a perspective view of my ear piercer;
FIG. 2 is a left side elevational view thereof, with the right side elevational view being a mirror image thereto;
FIG. 3 is a top view thereof;
FIG. 4 is a bottom view thereof;
FIG. 5 is a front view thereof;
FIG. 6 is a back view thereof;
FIG. 7 is a prospective view of a second embodiment of my ear piercer;
FIG. 8 is a left side elevational view thereof, with the right side elevational view being a mirror image thereto;
FIG. 9 is a top view of the FIG. 7th embodiment;
FIG. 10 is a bottom view of the FIG. 7 embodiment;
FIG. 11 is a front view of the FIG. 7 embodiment; and,
FIG. 12 is a back view thereof.
